UNITED STATES PATENT OFFICE.

EMANUEL W. DUNN, OF OAKLAND, CALIFORNIA.

ORCHARD-HEATER.

1,270,712.

Specification of Letters Patent. Patented June 25, 1918.

Original application filed September 9, 1912. Serial No. 719,291. Divided and this application filed December 15, 1913. Serial No. 806,782.

To all whom it may concern:

Be it known that I, EMANUEL W. DUNN, a citizen of the United States, residing at Oakland, in the county of Alameda and 5 State of California, have invented new and useful Improvements in Orchard-Heaters, of which the following is a specification.

This invention relates to open air heaters particularly adapted for heating a locality 10 or zone to prevent damage of fruit and the like by frost and freezing, although the invention is capable of other uses without material change. And, more particularly, this invention relates to a heater of the class described containing its own fuel reservoir for holding a sufficient supply of liquid fuel for a suitable period of operation.

It is one of the prime and underlying objects of my present invention to supply, in 15 such a heater as set forth, a simple and efficient air feed which is capable of supplying the liquid fuel with all the air necessary for complete and thorough combustion at any desired rate, and in such manner as to cause 20 the complete combustion of all of the fuel. By efficiently supplying air for combustion I provide that there shall be no liquid matter left unconsumed, either exterior to or interior of the heater. It has been shown to be 25 of great advantage to provide for perfect and sufficient combustion in order to prevent the deposition of oily soot and similar solid carbon and oil particles on the fruit which is being protected; and it also works greatly 30 for efficiency to consume these elements of fuel combustion, the combustion thereof adding greatly to the heat of the flame and to the heat deliverable to the surrounding locality.

40 My invention provides primarily an air feed leading from the top of the fuel receptacle or reservoir downwardly into the receptacle and discharging above the surface of the liquid fuel therein. This air feed 45 may be accomplished in many different manners, all having in common the general principle of a downward air blast. I have provided various devices for controlling the volume of air drawn into the heater and 50 for controlling the draft through the combustion opening or flue. These, and other various particulars of my invention will be explained in the following specification.

With a heater as above outlined I am enabled to deliver a large volume of heat units

which spread over the surrounding locality, heating the atmosphere therein and preventing frost by primarily preventing the lowering of temperature in the affected zone. The heated gases of combustion carry very little 60 or no solid matter which will deposit on the fruit and on other adjacent objects.

I will now proceed to a detailed explanation of my improved heater, reference being had to the accompanying drawings, in 65 which—

Figure 1 is a vertical cross section of the invention in its simplest form.

Figs. 2, 3, 4 and 5 are vertical sections 70 illustrating modifications of the invention.

Fig. 6 is a plan view showing the form of controlling means for the inwardly flowing air.

Referring now particularly to the drawings, my device consists essentially of a 75 liquid fuel receptacle or reservoir 20, a combustion outlet indicated generally by the number 21, and an air inlet or inlets indicated generally by the numeral 22. In each of the forms shown in the drawings it will 80 be noted that the combustion inlets are of such arrangement and design that the inward flow of air is formed into a downward blast or current which delivers over the surface of the liquid fuel within the reservoir, 85 and that the variations within the forms shown in the drawings are mere variations of different means for effecting this particular result. In some forms I may use a tube or tubes, which in effect merely extend the 90 opening downwardly toward the surface of the liquid. In some forms these tubes may be imperforate and there may be a number of tubes of various lengths, so that, no matter at what level the liquid within the reservoir may be, there will always be some tube or tubes discharging air downwardly onto the surface of the liquid.

In others these air inlet tubes may be perforated, as will be hereinafter described in 100 detail, and the air will then escape through said perforations directly above the surface of the liquid. In either form I provide for graduated distribution of the air for combustion, directly above the liquid surface; 105 and I also provide suitable means for regulating the inflow of air so as to thereby regulate the capacity and volume of flame issuing from the heater. It will also be noted that I have shown various forms of combus- 110

tion or discharge openings 21. In some of the forms the discharge opening may be a mere and simple opening or a single draft or combustion flue, in others the combustion flue may be provided with perforations; and the combustion flue may further be provided with a damper through which the volume and intensity of flame may be regulated. The combination of the air feed control and the damper control also affords means for regulating to a nicety the proportional supply of air for any given grade of fuel, so that the combustion may be regulated to be complete and thorough to consume every particle of fuel within the reservoir and to obtain therefrom every available heat unit.

It is one of the chief advantages of my present construction that I am enabled to consume all of the fuel within the reservoir, even consuming the heavy liquid matter of low grade crude oil which would otherwise be deposited in the bottom of the receptacle and there be sticky and difficult to remove. This feature is an important one, and one of which I will speak more fully hereinafter.

Referring particularly to Fig. 1, I will first explain one form of my heater, whence the other forms will be readily intelligible with short explanations of their different variations from the form first explained.

The air inlet 22 is continued downwardly from the cover 27 by a suitable tube 23, provided with openings or perforations 24, through which air is distributed over the surface of the liquid fuel 25; the combined areas of the perforations 24 being preferably not more than the cross sectional area of the tube 23 in order that air will be drawn to the bottom of the tube when the surface of the liquid fuel in the reservoir is low and when perfect combustion at the surface of the fuel is more particularly desired to consume the heavier particles of fuel. It can be readily seen that this provides for a downwardly directed blast of air delivered directly to the surface of the fuel, thereby promoting combustion at the surface of the fuel of the highest efficiency. The flame and gases of combustion pass upwardly through combustion outlet 21 which is continued upwardly by a suitable combustion and draft flue or stack 26.

In Fig. 2 I have shown a modified form of my improved device, similar to that shown in Fig. 1, and differing from it only in that the air inlet and combustion outlet are at the sides instead of through the cover of the reservoir. In Fig. 2 I have illustrated a form in which the reservoir 20^a is provided with a removable cover 27^a. The inlet and outlet flues may be mounted on the cover 27^a, but I have shown the cover as being in an unperforated piece, and have shown the inlet and outlet flues as being mounted on the

receptacle itself. The outlet flue 26^a may emerge from the upper portion of the side of the reservoir beneath the cover. The inlet flue 23^a may be constructed with a hood, as shown, so as to be water and rain proof. The advantage of this construction is that the cover has no openings or apertures through which water may gain access to the reservoir.

In Fig. 3 is shown another modification of my device. In this form I have designated the receptacle by the numeral 20^b, the air inlet or inlet by the numeral 22^b, and the combustion outlet by the numeral 21^b. In this form the inlet devices are formed by a series of openings 22^b in the upper portion of the cover 27^b. Some of the openings 22^b are shown extending only through the cover 27^b of the receptacle, while I have shown other of these openings as being extended downwardly into the receptacle by means of tubes 23^b. Tubes 23^b may be in groups of different lengths and each group may be arranged about the vertical axis of the receptacle. The tubes are preferably of different lengths, so that there will always be one or more of the tubes feeding air directly to the surface of the liquid fuel 25^b. As the fuel is consumed and the surface falls, the lower discharge ends of the tubes 23^b are uncovered, and the incoming air is then fed through the longest uncovered tube directly to the surface of the liquid fuel. This provides a downwardly directed blast of air delivered directly to the surface of the fuel, thereby promoting efficient combustion. The flame and gases of combustion pass upwardly and outwardly through combustion outlet 21^b.

In Fig. 3 the combustion outlet is shown confined within a suitable collar 30 within the combustion flue 26^b. Collar 30 may be provided with perforations or apertures 31, but this is not essential to the efficiency of the heater. The burning gases pass upwardly through the opening 21^b and through the collar 30, and thence upwardly through the stack 26^b and out through the damper controlled top 32. The damper controlled top 32 of the stack 26^b may be comprised in an apertured cap 33, surmounted by a damper member 34, having similar corresponding apertures which are adapted to either register with the apertures in the cap 33 or to be turned so as to shut off these apertures, either partially or entirely. Stack 26^b may be provided with suitable air inlet openings 35 through which air passes, as indicated by the arrows, passing upwardly and around the perforated collar 30. The flame and gases passing upwardly through the outlet 21^b receive auxiliary air through these openings 30; the result being the complete combustion of all parts of the fuel. The relative amount of flame and

heated gases of combustion delivered may be regulated by varying the size of the openings in the top of the combustion flue 26^b. The combustion may be controlled by suitable dampers 40^b, over the air inlets, to control the admission of air and the amount of vapor generated.

I have shown in Fig. 4 a form in which the air inlets 35^b, around and in the base 10 of the stack 26^a, are controlled by a sliding damper or shutter 41, with holes 42 adapted to register with the apertures 35^b. The admission of auxiliary air to the stack to regulate combustion may be thus controlled. The 15 air inlet openings 22^c in the cover may be controlled individually, as shown in Figs. 1, 3 and 6, or they may be controlled by a ring damper 40^c, having holes 23^c to register with the openings 22^c. In any case the flow of air 20 to the fuel through the inlet openings 23^c in the cover may be regulated so that any desired degree of richness of gas is picked up from the fuel and carried into the combustion stack, while the amount of auxiliary 25 air to the combustion chamber in the stack may be regulated to produce efficient and complete combustion of the gases.

In Fig. 5 I have illustrated a similar form in which I have shown an imperforate tube 30 25^d discharging air out of its lower end only.

By properly proportioning the air inlet and the combustion outlet and the size of the reservoir, it is possible to make a device of this character which will burn a fuel of a 35 certain gravity in certain quantities per hour. Thus, the device may be properly proportioned to cause three gallons of, say, 28 gravity distillate to burn for a certain number of hours. This would be true of the 40 device in its simplest form. By the addition of damper regulators to the inlet and outlet the device may be suited to oils of different gravities.

Another feature which I may mention is 45 the adaptability of my device to any kind of receptacle or reservoir. It is greatly commercially desirable that my device be capable of use with receptacles or pots which may be possessed by the users of my apparatus. It will be seen that, all of the flues 50 and tubes being made on the cover of my device, the cover may be made to fit upon a receptacle of any character and configuration, thereby transforming that old device of 55 which the receptacle forms a part into my new improved heater.

This application is a division of my original application Serial Number 719,291, filed September 9, 1912.

Having thus described my invention, what 60 I claim and desire to secure by Letters Patent is—

1. An orchard heater comprising a fuel 65 receptacle having a cover and provided with a combustion opening, means for taking air

directly from the atmosphere and discharging the same outwardly within the receptacle and at progressively different levels as the fuel is consumed.

2. An orchard heater comprising a fuel 70 receptacle having a combustion opening at the top thereof, and means for directing atmospheric air downwardly into said receptacle from a zone above said top to progressively different levels within the receptacle 75 and at points eccentrically positioned with respect to said combustion opening.

3. An orchard heater comprising a fuel 80 receptacle having a cover and an opening in the cover, means for directing atmospheric air through the cover into the receptacle to the surface of the oil therein, and a stack extending upward from said cover and communicating with said opening, said stack 85 having a plurality of circumferentially arranged perforations positioned in a plane wholly above the cover and directly open to the surrounding atmosphere.

4. An orchard heater comprising a fuel 90 receptacle having a cover provided with a combustion opening therein, means for taking air directly from the atmosphere and discharging the same outwardly within the receptacle and at progressively different levels as the fuel is consumed, and a stack 95 extending upward from said cover and communicating with said combustion opening, said stack having a plurality of circumferential perforations positioned in a plane 100 above the cover and directly open to the atmosphere.

5. An orchard heater comprising a closed fuel receptacle having an upper combustion opening, a stack extending upward from said opening and provided with perforations 105 open to the atmosphere for the admission of auxiliary air, and a draft inlet tube having its upper end also open to the atmosphere and extending downward into the receptacle, said draft tube having means whereby 110 the air as it is admitted may be delivered at progressively different levels as the fuel is consumed.

6. An orchard heater comprising a closed fuel receptacle having an upper combustion 115 opening, a stack extending upward from said opening and provided with perforations open to the atmosphere for the admission of auxiliary air, and a draft inlet tube having its upper end open to the atmosphere and extending downward into the receptacle being provided with vertically spaced perforations 120 whereby the air entering the receptacle may be delivered at progressively lower levels as the fuel is consumed.

7. An orchard heater comprising a closed 125 receptacle, a stack extending from the top of said receptacle and through which the products of combustion are conducted, and a draft inlet tube extending inward into the 130

receptacle and having its upper end open to the atmosphere, being provided with means whereby the air admitted may be delivered at progressively lower levels as the fuel 5 within the receptacle is consumed.

8. An orchard heater comprising a receptacle provided with a removable cover, a stack attached to said cover through which the products of combustion are conducted, 10 and a draft inlet tube depending from said cover and suspended within the receptacle, said draft inlet tube having means whereby the air admitted to the receptacle may be delivered at progressively lower levels as 15 the fuel is consumed.

9. An orchard heater comprising a closed receptacle, a stack extending from the top of said receptacle through which the products of combustion are conducted, and a 20 draft inlet tube extending inward into the receptacle, said draft inlet tube being provided with means whereby the air admitted may be delivered at progressively lower levels as the fuel within the receptacle is 25 consumed, and means for controlling the volume of air entering said draft inlet tube.

10. The combination in an orchard heater of a liquid containing receptacle having a cover, said cover having a stack and an air 30 tube supported in the receptacle above the liquid body and having an inlet communicating with the atmosphere and constructed and arranged to direct a down-draft onto and over the fuel level approximate to the 35 zone of combustion, said air tube being to one side of the stack.

11. The combination in an orchard heater of a liquid containing receptacle having a cover, said cover having a stack and an air 40 tube supported in the receptacle above the liquid body and having an inlet communicating with the atmosphere and constructed and arranged to direct a down-draft onto and over the fuel level approximate to the 45 zone of combustion, said air tube being to one side of the stack, said tube having perforations throughout its length whereby the air is admitted to the immediate surface of the fuel as the latter recedes.

50 12. The combination in an orchard heater of a liquid containing receptacle having a sloping cover, said cover having a stack and an air tube supported in the receptacle above the liquid body and having an inlet communicating with the atmosphere above the liquid body and having an outlet to the atmosphere and constructed and arranged to direct a down-draft onto and over the fuel level approximate to the zone of combustion, 55 said air tube being to one side of the stack, said tube having means in its length whereby the air admitted through the tube is delivered to the surface of the fuel irrespective of the level of the latter.

60 13. An orchard heater, comprising a

liquid fuel receptacle, a closure cover therefor provided with a combustion opening, a draft stack extended outwardly therefrom, and air inlet means independent of the stack extended downwardly from the cover and 70 into the fuel receptacle, said means open to the atmosphere and arranged and constructed to direct a down-draft onto and over the fuel level within the fuel receptacle and approximate to the zone of combustion and at progressively lower levels as the fuel is consumed.

14. An orchard heater, comprising a liquid fuel holding receptacle having a cover provided with a combustion outlet, a perforated draft stack projected from said cover and embracing the combustion outlet thereof, and means independent of the stack extended within the fuel holding receptacle for supplying air thereto, said means being 80 open to the atmosphere and so arranged relative to the receptacle as to discharge air onto the liquid approximate the zone of combustion and at progressively lower levels as the fuel is consumed.

90 15. An orchard heater, the same comprising a liquid fuel holding receptacle having a cover provided with a combustion outlet, a draft stack upwardly projected from the combustion outlet of the cover, and means 95 independent of the stack for admitting air within the holding receptacle, said means being open to the atmosphere and provided with a plurality of outlets for the discharge of air into the receptacle and onto the 100 liquid therein approximate the zone of combustion and at progressively lower levels as the fuel is consumed.

16. An orchard heater comprising an oil receptacle, a cover therefor, a stack mounted 105 on said cover through which the products of combustion are conducted, and a perforated draft-inlet tube mounted in said cover and suspended within said receptacle, the perforations of said tube being distributed 110 throughout the length of the latter whereby they are successively uncovered as the fuel is consumed for increasing the volume of air admitted to the receptacle.

115 17. An orchard heater comprising an oil receptacle, a cover therefor, a stack mounted on said cover through which the products of combustion are conducted, and a perforated draft-inlet tube mounted in said cover at a point laterally of said stack and 120 suspended within said receptacle, the perforations of said tube being so distributed throughout its length that an ever-increasing volume of air is admitted therethrough to the receptacle as the level of the oil is 125 lowered.

18. An orchard heater comprising an oil receptacle, a cover therefor, a stack mounted on said cover through which the products of combustion are conducted, and a per- 130

forated draft-inlet tube removably mounted in said cover at a point laterally of said stack and suspended within said receptacle, the perforations being so distributed throughout the length of said tube that an ever-increasing volume of air is admitted to the receptacle as the level of the oil is lowered, and controllable means for regulating the draft through the upper end of said tube.

19. In an orchard heater, the combination with a liquid fuel container having a cover with a stack through which products of combustion are permitted to escape, of means for gradually increasing the air supply to the container as the level of said fuel is lowered, said means comprising a perforated draft tube projected through said cover and depending within the container to a point adjacent to the bottom of the latter, the per-

forations being distributed throughout substantially the entire length of said tube.

20. In an orchard heater, the combination with a liquid fuel container having a cover with a stack through which products of combustion are permitted to escape, of a draft tube located within said container at a point laterally of said stack and communicating with the atmosphere through said cover, said tube having openings therein through which air is admitted to the container in increasing volume as the level of the fuel is lowered.

In testimony whereof I have hereunto set my hand in the presence of two subscribing witnesses.

EMANUEL W. DUNN.
